CLAIM

The ornamental design for an automotive vehicle, as shown and described.

DESCRIPTION

FIG. 1 is a perspective view from the top of an automotive vehicle showing our new design;

FIG. 2 is a side elevation view thereof, both sides being mirror images of each other;

FIG. 3 is a top plan view thereof;

FIG. 4 is a front elevation view thereof; and,

FIG. 5 is a rear elevation view thereof.

The claimed design is for product configuration; lines shown on product surface are shade lines and not surface decoration.
